UNITED STATES PATENT OFFICE.

GUSTAVE ANTOINE LAMBERT AND HENRI ALEXANDRE CARDOZO, OF PARIS, FRANCE.

ROLLING APPARATUS.

No. 802,048.

Specification of Letters Patent.

Patented Oct. 17, 1905.

Application filed January 4, 1905. Serial No. 239,679.

To all whom it may concern:

Be it known that we, GUSTAVE ANTOINE LAMBERT, civil engineer, residing at No. 44 Rue du Ranelagh, and HENRI ALEXANDRE CARDOZO, civil engineer, residing at No. 62 Rue de Tocqueville, Paris, in the Republic of France, citizens of the Republic of France, have invented certain new and useful Improvements in Rolling Apparatus, of which

10 the following is a specification.

It is recognized that in rolling metal bars and the like by means of a system of planetary rolls—that is, by means of sets of rolls revolving around one axis—there are always 15 formed on the rolled surface undulations more or less pronounced, which necessitates a supplementary rolling or drawing operation in order to produce a plane even surface. This is due to the circumstance that the rolls 20 while describing a circle rise from the work immediately after striking the same, and therefore do not remain for sufficient length of time in contact with the work.

The present invention has for its object to 25 overcome this objection by means of an arrangement which enables the rolls after striking the work to continue to exercise a rolling action thereon while moving for a short distance along a straight path. To this end 30 the path of the revolving axes of the rolls is determined by a guide engaged by guide-rollers carried by said rolls and having a definite contour which causes the rolls when brought in contact with the work to remain in contact 35 therewith, and so exercise a rolling or drawing action and remove the undulations as produced.

In the accompanying drawings, which illustrate the invention, Figure 1 is a vertical section of the improved apparatus on the line A A of Fig. 2. Fig. 2 is a horizontal section on the line B B of Fig. 1. Fig. 3 is a section on the line C C of Fig. 2, and Fig. 4 is a section through one of the disks carrying the 45 journals of the rolls.

The rolling-mill comprises two sets of rotatable rolls *a* of the number two, four, or the like in each set. In the drawings annexed four rolls are shown in each set. These rolls are 50 mechanically revolved at a very high speed around two shafts *b*, disposed and driven as in the usual analogous systems. The journals *c* of said rolls are loosely mounted in bushes *d* capable of free radial movement on plates or

disks *e*. These disks, of the number of four, 55 are disposed in pairs on both sides of said rolls *a* and are fast on the rotating shafts *b*. They are provided with radial notches or slots in which are free to move the bushes *d*, the said notches being shown symmetrically disposed in respect of the two pairs of disks. The spindles of the rolls terminate at each extremity in guide-rollers *f*, which, however, might be next the central rolls or in one piece therewith. 60

The rollers *f* are directed by guides *g*, formed in the brackets, serving to support the bearings of the shafts *b*. Each of the guides *g* includes a straight part *h* *i*, Fig. 3, connected by a suitable curve *i* *j* with the rest of 70 the path, which is perfectly circular, the said straight parts being at the position where the rolls of both sets come into contact with the work.

It will be readily understood that if the 75 shafts *b* turn in the direction indicated by the arrows and at a very high speed the rolls *a* when they come in contact with the work will continue to remain in contact therewith and will move in a straight path corresponding to 80 the part *h* *i* of the guide by reason of the centrifugal force which tends to apply the rollers *f* against the guides *g* and by virtue also of the arrangement of the disks *e*, which 85 enables the journals of the rolls to move radially. In this way the rolls when they arrive at the point *h* continue their rolling action in a straight line instead of rising according to the tangential circumference at *h*, as was the case in ordinary systems. The surface is 90 thus rolled flat, and the undulations unavoidably produced in all systems of planetary rolling apparatus are flattened out.

The speed of rotation of the shafts *b* should be such that whatever be the weight of the 95 rolls, which weight varies according to the work being passed through, the centrifugal force developed should always exceed the force necessary to bring the rollers against the guide, the excess of this force being determined by the metal being treated.

Having now described our invention, what we claim as new, and desire to secure by Letters Patent, is—

1. A rolling apparatus comprising two co-operating sets of planetary rolls *a* between which the work is led, in combination with two rotatable shafts *b* about which respec-

tively each set of rolls is adapted to revolve, disks *e* mounted fast on each shaft and upon which are loosely mounted the journals *c* of the said rolls, and stationary guides *g* comprising a curved part and a short straight part upon which the journals of the rolls *a* are adapted to move, substantially as and for the purpose set forth.

2. A rolling apparatus comprising two operating sets of planetary rolls *a* between which the work is led, in combination with two rotatable shafts *b* about which respectively each set of rollers is adapted to revolve, disks *e* provided with radial slots and mounted fast on each shaft, bushes *d* slidably mounted on said radial slots and in which are loosely

mounted the journals *c* of the rolls *a*, guide-rollers *f* connected to the rolls *a*, and stationary guides *g* upon which are adapted to move said guide-rollers comprising a curved part and a short straight part leading from the point where the rolls come in contact with the work, substantially as and for the purpose set forth.

In testimony whereof we have signed our names to this specification in the presence of two subscribing witnesses.

GUSTAVE ANTOINE LAMBERT.
HENRI ALEXANDRE CARDODOZO.
